UNITED STATES PATENT OFFICE.

GLENN MORE, OF JAMESTOWN, NEW YORK, ASSIGNOR TO BLACKSTONE MANUFACTURING COMPANY, OF JAMESTOWN, NEW YORK, A CORPORATION OF NEW YORK.

SWINGING-WRINGER MECHANISM.

Application filed February 7, 1921. Serial No. 443,216.

To all whom it may concern:

Be it known that I, GLENN MORE, a citizen of the United States, residing at Jamestown, in the county of Chautauqua and State of New York, have invented certain new and useful Improvements in Swinging-Wringer Mechanism, of which the following is a specification, reference being had to the accompanying drawings, and to the reference characters marked thereon, which form a part of this specification.

This invention relates to wringer mechanism adapted for use on washing machines. The object of the invention is to provide a swinging wringer and mechanism therefor which can be readily embodied in any washing machine and particularly motor driven machines; which mechanism will be positive in its action and very simple to operate.

Another object of the invention is to provide simple means whereby the wringer proper may be very readily attached to the wringer operating mechanism, and the whole, as a unit, be readily attached to or removed from the washing machine for shipment or other purposes; and which will also, when attached to the machine, be readily turned about a vertical axis without affecting its driving connections so that the wringer may be operated in use either over the washing machine frame or over a wash tub at either side of the washing machine.

A further object of my invention is to provide such a removable swinging wringer mechanism with a reversing mechanism for rotating the wringer rolls in either direction, and from at least two different sides of the washing machine.

A further object of the invention is to provide locking means for holding the wringer mechanism in any of its changed positions relatively to the washing machine.

A further object of the invention is to provide a construction of the kind described, in which the frame to which the wringer proper is attached is very solidly mounted upon a fixed support attached to the washing machine, but in such manner as to enable the wringer device, as a unit, to be very easily turned about its vertical axis when desired.

The invention comprises the construction and arrangement of the parts as illustrated and hereinafter described, and its objects

and advantages will be more fully comprehended as I proceed with my specification.

In the drawings: Fig. 1 is a plan view of any conventional washing machine, showing my swinging wringer attachment applied thereto, and a tub supporting frame attached and illustrating in dotted and full lines the wringer mechanism in two different positions.

Fig. 2 is a side elevation, enlarged, of the swinging wringer mechanism and fixed support upon which it rests.

Fig. 3 is a view similar to Fig. 2, with the wringer in a changed position with respect to the support.

Fig. 4 is a plan view of the fixed support.

Fig. 5 is a vertical sectional view of the wringer operating mechanism, showing the driving and reversing gears in elevation.

Fig. 6 is a vertical sectional view of the same, taken upon the plane indicated by the dotted line 6-6 of Fig. 5, and looking in the direction indicated by the arrow.

Fig. 7 is a horizontal, sectional plan view taken upon the plane indicated by the dotted line 7-7 of Fig. 6 and looking in the direction indicated by the arrow.

Fig. 8 is a detail view, in vertical section, showing the depending pins and associated parts.

In the drawings, A represents a conventional type of washing machine frame, having tubs B and C positioned thereon. D is a standard on the frame. E is a wringer mechanism, as a whole, and F the actuating device therefor, as a whole. G represents a metal support which may be secured in any convenient manner to the standard D. The mechanism F is mounted on the fixed support G.

The wringer E comprises vertical and horizontal frame members 1, 1^a, and a pair of wringer rolls 2, 2, one of which is provided with an operating shaft 3. This wringer E will be secured in any convenient manner to a bracket member composed of parts 4, 4^a. The part 4 is provided with a vertical face 5. The part 4^a is provided with a similar vertical face 5^a and a supporting shoulder at an angle thereto indicated at 6. The two parts 4 and 4^a are adapted to fit against each other in such manner as to form a journal bearing 7 for the shaft 3. The member 4 also includes a

2 dome-like housing member 8 having a circular exterior flange 9, and the member 4^a is provided with a circular, apertured body 10 of an external diameter equal to that of the flange 9. Below the part 10 is a locking ring 11. Bolts 12 pass through the flange 9, the member 10, and are screwed into the ring 11, thus locking the parts firmly and securely together, as will be readily understood. The interior diameter of the part 10 will correspond with the interior diameter of the dome-like part 8. A spherical, or cup-shaped member 13, having an interior diameter similar to that of the part 8, is provided at its upper and larger end with an outwardly extending flange 14. Its lower end is provided with a suitable aperture which contains a bearing pin 15. This pin 15 extends below the outer surface of the member 13, for a purpose hereinafter set forth. The member 10 is interiorly recessed to accommodate the flange 14 of the lower member 13. It will be noted that the interior diameter of the ring 11 is equal to the exterior diameter of the flanged end of the cup-shaped member 13, thus affording a shoulder or support for the flange 14, and providing for relative rotative motion between the cup-shaped member 13 on the one hand, and the dome-like part 8 and associated parts on the other hand.

Upon the shaft 3 are loosely mounted two oppositely facing beveled gears 16, 16, each having on its face clutch fingers 17, 17. Intermediate the clutch fingers of said gears, is a clutch spool 18, suitably secured to the shaft 3 by a spline 19, so as to be moved longitudinally of the shaft 3 and to rotate therewith. On each end of the spool 18 are clutch fingers 20, complementary with the clutch fingers 17 of the beveled gears 16. An actuating yoke 21 having operative engagement with the spool 18 is mounted upon the pin 15 and through the top of the member 8 in such manner as to have movement about the vertical axis of the pin 15, thereby actuating the spool 18 along the shaft 3, toward one or the other of the gears 16, 16. As shown in Figs. 5 and 7, the spool 18 is, in its neutral position, disconnected from the clutch fingers, but it will be readily understood that when moved in one direction, the adjacent clutch fingers will engage, and that beveled gear 16 whose clutch fingers are thus engaged, will thereby be locked to the shaft 3 and rotate therewith.

Upon the pin 15, which functions also as a shaft, is a beveled gear 22, the teeth of which mesh with the teeth of both of the beveled gears 16, 16. The gear 22 is a driving gear and it follows that when the clutch 18 is in the neutral position, the shaft 3 will be out of operation. When the clutch 18, however, is engaged through adjacent

clutch teeth with one of the gears 16, say the left hand gear, the shaft 3 will be driven from the gear 22 through the engaging gear 16 in one direction, and the shaft 3 will be driven in the reverse direction when that gear 16 is disengaged and the other gear locked to the shaft 3 by the shifting of the clutch 18. This three-way gear reversing device, per se, is old in the art and its operation is so familiar that further explanation will not be deemed necessary in this specification.

Connected with the gear 22 and preferably integral therewith as herein shown, is a second beveled gear 23. A suitable aperture or opening in the member 13, and indicated at 24, is made opposite the gear 23 so as to expose a portion of said gear 23 to view, as clearly indicated in Fig. 2.

Upon the fixed support G is mounted a beveled gear 25, the teeth of which are adapted to mesh with the teeth of the gear 23 when the two are placed in juxtaposition. The gear 25 may be operated by a train of gears 26, 27, or otherwise, from any suitable source of power on the washing machine.

A suitable recess or socket 28 is located in the support G, the central longitudinal axis of which socket is at right angles to the axis of the shaft on which the gears 25, 26 are mounted. It will be manifest, therefore, that when the parts are placed together, the pin 15 will register with and enter the recess 28 and the hub on the lower surface of the cup-shaped part 13 will rest upon the surface 30 of the support G.

The support G also has another recess 31 of somewhat larger diameter than the recess 28, in which a fixed pin or dowel member 32 may be entered, said pin 32 being secured to and depending from a hub or post 33, integral with and depending from the cup-shaped member 13. These two bearing pins 32, 15, entering the sockets 31, 28, respectively, will accomplish the proper registration of the parts and prevent any lateral misplacement thereof in operation, while at the same time affording means whereby the entire wringer mechanism E, F, as a unit, may be lifted vertically and removed from the support G. The separation of these parts will be accomplished, however, only when the locking latch has been thrown. Said locking latch is shown in Figs. 2 and 3, and comprises the arm 34, pivotally mounted at 35, to the lugs on the cup member 13, and having at one end a hand piece 36. The other end of the pivoted arm 34 is recessed at 37, which affords at its lower end a locking hook. The recess 37 is adapted to engage the support G at 38 and is normally held in the engaged position by reason of the spring 39 or other suitable means. When it is desired to separate the parts, pressure

is applied to the under side of the thumb piece 36, the spring 39 is compressed, and the lower end of the pivoted lever 34 moving away from contact with the support G, it follows that the wringer mechanism E, F, 5 may be bodily lifted away from the support G. Similarly, when the parts are brought together, the spring 39 pressing the thumb piece outwardly will normally swing the 10 lower or recessed end of the latch 34 into proper position to engage the part G and lock them together.

The face of the flange 14 of the cup member 13 is recessed at suitable intervals indicated by 40. Within the member 8 is a pivoted locking latch 41, the lower end of which is adapted for engagement with one of the recesses 40, and held in such normally engaged position by the spring 42. A thumb 15 member or operating handle 43 projects outwardly through the shell of the member 8 for ready access of the operator; when it is desired to shift the position of the parts 8, 10 and 11, with respect to the fixed position 20 of the part 13, the operator depresses the thumb latch 43 against the normal action of the spring 42, thereby moving the locking latch 41 inwardly and out of engagement with the notch 40. Thereupon, the parts being thus unlocked, they may be given rotary motion with respect to each other, about the central vertical axis of the shaft or pin 15. This will enable the operator to shift the position of the wringer E, as desired, and to lock the wringer in its desired 25 position, for the reason that the spring 42 will cause the lower end of the locking latch 41 to automatically engage the recess 40 as soon as the new position is arrived at.

Means for actuating the yoke 21 are provided as follows: To the upper end of the yoke 21, which projects through the top of the member 8, I pivotally secure one end of a reversing lever 44. This lever is provided 30 with two engaging locking flanges 45, 45. On the top of the member 8 are a pair of concentrically arranged flanges 46, diametrically positioned with respect to each other, and each containing three notches or 35 recesses 47. The flanges 45 are adapted to fit in these notches or recesses 47. The arrangement of the parts is such that when the flange 45 is in the central notch, the yoke 21 has moved the clutch member 18 into the neutral position, and when the lever is moved so as to bring the flanges 45 in the notches 47, the yoke has accordingly 40 moved the clutch member 18 so as to lock one or the other of the beveled gears 16 to the shaft and thus operate the shaft 3 to the right or left, as the case may be.

It will be noted that the pivotal connection of the arm 44 with the upper end of the yoke 21 is such that the arm may be thrown on one side, as shown in Figs. 6 in

full lines, or on the other side of the yoke, as shown in dotted lines in Fig. 6, so as to be in convenient access to the operator. Instead of the operator walking around the machine to take hold of the handle 44, the 70 handle may be swung about its pivotal connection to be within easy reach of the operator.

It will be noted that the members 8 and 15 75 are so shaped as to constitute in effect housings for the reversing gearing and other mechanism, and thus protect the operator against accident.

It will be observed that the wringer and connections E, F, may be readily and 80 quickly unlocked and removed from the washing machine by any unskilled person, who simply lifts up the thumb latch 36 and then bodily raises the part F so as to disengage it from the part G, and that the assembling of the parts may be accomplished with equal facility by an unskilled person. This is of great advantage in the practical 85 operation of the machine and the ease with which the parts can be assembled and disassembled, and facilitates packing and shipping of the machine.

It will also be observed that the swinging of the wringer E into different positions about the axis of the shaft F as a center is 90 accomplished easily and readily,—not by having the entire part F swing with respect to the support G, but by having the bracket member 10 and the parts associated therewith, swung in a horizontal plane about the 95 flange 14 when the thumb lever 43 is depressed.

It will also be noted that the wringer may not be shifted from one position to another without first moving the reversing lever 44 into the "neutral" position,—that is to say, so that its flange 45 will engage the central recess 46. It will be observed that the inner face of the spring actuated latch 41 is suitably notched to span the yoke 21, when the latter is in the intermediate or neutral position only.

I claim as my invention:

1. The combination with a wringer mechanism, of a fixed support, a two-part housing, the upper part being movable in a horizontal plane about the lower part, means for removably securing the lower part to said fixed support, said means including depending pins on said lower part, and a hand operated latch member on the lower part adapted to secure the latter to the support.

2. In a wringer mechanism, the combination with a fixed support, of a two-part housing, the upper part being connected to the wringer and movable in a horizontal plane about the lower part, gear mechanism in the housing for operating the wringer, and means on the lower housing to prevent its rotation with respect to the fixed sup-

port, said means including depending pins on the lower housing, and a hand operated means on the lower housing to lock the latter to the support, the longitudinal axis of one of the said depending pins being coincident with the axis of rotation of a rotatable element of the gear mechanism.

In testimony that I claim the foregoing as

my invention I affix my signature, in the presence of two witnesses, this 3rd day of ¹⁰ Feb., 1921.
